UNITED STATES PATENT OFFICE

2,566,637

TUYÈRE CHANGING MACHINE

Roy A. Roberts, Phalanx, Ohio

Application January 2, 1946, Serial No. 638,679

1 Claim. (Cl. 29—200)

1

The invention relates to a parts changing machine for blast furnaces, and more especially to a tuyère changing apparatus for use in blast furnaces or the like.

The primary object of the invention is the provision of an apparatus of this character, wherein the blow pipe and tuyère with adjuncts thereto can be readily and easily removed and placed from and to a blast furnace or the like with ease and dispatch, without requiring excessive manual labor for so doing, the apparatus being of novel construction and is unique in the arrangement of its parts.

Another object of the invention is the provision of an apparatus of this character, wherein a burnt out tuyère of a blast furnace can be detached with ease and dispatch, and without manual handling thereof, and a new tuyère placed into position likewise with ease and dispatch and without requiring manual handling thereof and the adjuncts thereto.

A further object of the invention is the provision of an apparatus of this character, wherein it is portable, so that the same can be conveniently brought into position for the purposes intended thereof, and the adjustment of such apparatus is manually effected with ease and dispatch.

A still further object of the invention is the provision of an apparatus of this character, which is simple in construction, thoroughly reliable and efficient in operation, strong, durable, possessed of few parts, readily and easily adjusted for the handling of the work operated upon thereby, and inexpensive to manufacture and install.

With these and other objects in view, the invention consists in the features of construction, combination and arrangement of parts as will be hereinafter more fully described, illustrated in the accompanying drawings, which show the preferred embodiment of the invention and pointed out in the claim hereunto appended.

In the accompanying drawings—

Figure 1 is a side view of the apparatus constructed in accordance with the invention in position for the changing of a blast furnace tuyère.

Figure 2 is a view similar to Figure 1 showing the apparatus adjusted for withdrawing the tuyère.

Figure 3 is an end elevation of the apparatus.

Figure 4 is a fragmentary enlarged sectional view taken on the line 4—4 of Figure 2, looking in the direction of the arrows.

Figure 5 is a fragmentary sectional view of the tuyère similar to Figure 1, showing the keyed arrangement of the apparatus therewith.

Figure 6 is a top plan view of the apparatus.

Figure 7 is a fragmentary side view showing

2

by dotted lines the manner of carrying the blow pipe for the furnace when handled by the apparatus.

Figure 8 is a sectional view taken on the line 8—8 of Figure 7, looking in the direction of the arrows.

Fig. 9 is a fragmentary view partly broken away of the bridle bolt assembly and its associated parts.

Similar reference characters indicate corresponding parts throughout the several views in the drawings.

Referring to the drawings in detail, A designates generally a blast furnace tuyère through 15 which enters the hot blast to the furnace, a portion of the latter being identified at B, this tuyère as usual is associated with a blow pipe 10, and adjuncts thereto, these being protected from intense heat inside the furnace by water 20 coolers 11 and 12, respectively, while the pipe has association with an elbow blow stock 13, including a ball-flange coupling 14 with the blow conduit 15, these being of the common or well known construction.

25 A blow pipe seat 16 is provided on the stock 13, and the coupling 14 has the link 17 connection with the stock 13, by a key 18, and an adjunct of the said stock 13 is a bridle bolt 19 which also includes a key 20 and a tensioning spring 21, respectively.

30 The tuyère changing apparatus constituting the present invention, comprises a carriage 22 provided with caster wheels 23 beneath the base of its chassis frame 24, so that the carriage can be moved from one locality to another, and brought 35 into position for operation. For a distance vertically at opposite ends of the carriage 22 is disposed upstanding corner feed screws 25, each rotatably supported in fixed upper and lower brackets 26 and 27, respectively, vertically spaced 40 from each other on the carriage. These screws 25 adjustably feed crosswise raising and lowering rails 28 at opposite ends of such carriage, while mounted centrally superimposed on these rails 28 in a longitudinal direction of the carriage 22 is a platform 29 which is horizontally arranged and equipped therewith is a similarly arranged feed screw shaft 30, suitably supported in bearings 31 at opposite ends of the platform. The shaft has threaded thereto a shiftable block-like runner 32, which is moved back and forth 45 through the use of the worm gear and pinion 33 and 34, respectively, meshing with each other, and operated by a hand wheel 35, the gear and pinion being located at the end of the platform 50 remote from the approaching end of the carriage to the work to be operated upon.

Carried by the runner is a ram 36, which at its inner downwardly curved end 37 has connection with the runner by a pivot 38 for vertical swing- 55

ing movement of such ram. This ram is fitted with a detachable hammer head 39 by a releasable pin 40, at the outer end of such ram, while provided inwardly of the latter with respect to the head is a wedge key slot 41 for a removable wedge key 42. This head and key enable the placement or removal of the tuyère tip created by the cooler 11, as best seen in Figures 2, 4 and 5 of the drawings, in the use of the ram. In Fig. 2 the head 39 is shown in position to remove the tuyère. The head 39 will enter the tuyère and it is then adjusted so that it will engage the marginal rim of the tuyère to permit its removal.

The ram 36 is angularly swingable vertically by a rocking elbow 43, connected by a pivot 44 forwardly of the pivot 38 for the said ram. The elbow 43 is adjusted by a feed screw 45 supported in the bearing 46 rising vertically from the runner 32 and of upwardly tapered formation, the screw 45 being engaged with the elbow 43 by a loose pin and slot connection 47 with the latter, while such screw is adjusted by a worm gear and pinion 48 and 49, respectively, hand driven at 50.

The feed screws 25 have associated therewith hand driven gearing 51 for the raising and lowering of the platform 29 to different horizontal planes in placing the tuyère and its removal to and from the furnace, together with adjuncts of such tuyère.

Built with opposite sides of the carriage 22 at the top longer edges thereof are horizontal tracks 52 forming guides for a pair of opposed movable runners 53, each carrying a ram 54 of short formation, and also horizontally arranged, and has a detachable and adjustable hammer head 55, the tracks 52 being fitted to feed screws 56, each operated by hand actuated worm gear and pinion connections 57, and this screw is threaded into the runner 53 companion thereto, so that it can be moved forwardly and backwardly, as may be desired. The hammers 55, each is for driving and releasing the key 18 in the path thereof, one at each side of the stock 13 in association with the coupling 14, before described.

The ram 36 has detachably fitted therein a pair of spaced stirrups 58 which are of hook form, and these are adapted to accommodate the blow pipe 10 when released from the tip formed by the cooler 11 and extracted from the cooler 12, or for placement therein, as best seen in Figures 7 and 8 of the drawings.

The ram 36 is also usable for releasing or applying the key 20 of the bridle bolt 19, in that the tension of the spring 21 can be relieved for such release and application of this key 20, as best seen in Figure 1 of the drawings.

The removal of the key 20 is accomplished by the spring engaging and compressing member 59 which is adapted to be removably positioned in the openings 60 in the ram 36. In Figs. 2 and 5 the member 59 is positioned out of position for engagement with the spring 21 but in Fig. 1 the member 59 is shown compressing the spring 21 to permit the removal of the key 20.

There has thus been provided a tuyère changing machine which is equipped with power hammers 55 that can be positioned as desired to drive the key 18 in or out of the link 17, a ram 36 that can be positioned at various angles by means of the screw 45 powered by the gear and pinion 48 and 49 respectively, the screw being mounted on a runner 32. The runner 32 engages the carriage 29 and is moved back and forth by means of the gear and pinion 33 and 34 respectively.

The carriage 22 is adjustable at each corner by means of the screws 25.

In use, the ram 36 compresses the spring on the bridle bolt 19 until the key 20 thereon can be removed. The runner 32 is then moved rearwardly to permit the bridle bolt to fall clear, causing the blow pipe 10 to move the stock 13 back to clear, and the pipe 10 is suspended in position by the stirrups 58. The ram 36 is then moved forward enough to let the blow pipe clear the seat 16. The ram is then inserted through enough for the head 39 to engage the nose of the tuyère while it is pulled out. The new tuyère is picked up by the ram, the key 42 is inserted, and the ram forces the new tuyère into position. The blow pipe is then placed in the seat 16 of the stock 13. The stock is then lowered into position, the bridle bolt is raised into place and spring compressed until the key 20 can be replaced. The stock 13 is then raised into position by driving the key 18 into the link 17 with the power hammers 55.

The apparatus does not of itself place the pipe 10 and stock 13 in position. After the tuyère has been inserted into position the apparatus is removed from its inserting position and the pipe 10 and stock 13 are manually positioned. Then the apparatus is returned to position so that the power hammers 55 can place the keys 18 into position. The apparatus is adapted to be moved into and out of position to pull or push the tuyère for the removal or insertion thereof. In other words by manually pushing the apparatus the tuyère is inserted and by manually pulling the apparatus the tuyère is removed. Thus the action is accomplished by a manually movable apparatus and not a fixed apparatus. The apparatus is not held stationary during the pulling and pushing of the tuyère for the removal and insertion thereof. Therefore there is no necessity to provide means for the anchoring of the apparatus.

What is claimed is:

In an apparatus of the kind described, having a carriage provided with a bottom chassis frame having rollers, raising and lowering cross rails located at opposite ends of the carriage, means for raising and lowering the said rails, a platform carried by the rails, a runner movable back and forth on the platform, means for moving the runner, the improvement comprising a vertically swingable ram fitted to the runner, means for adjustably swinging the ram to working positions, said means comprising a rocking elbow engageable with the ram, a carriage to which the ram and rocking elbow is pivotally connected and operational means engaging said carriage and said rocking elbow whereby said ram is operated.

ROY A. ROBERTS.
